UNITED STATES PATENT OFFICE

FRANK E. AUSTIN, OF HANOVER, NEW HAMPSHIRE, ASSIGNOR OF ONE-HALF TO
HARRY E. HILLMAN, OF HANOVER, NEW HAMPSHIRE

HURDLE

Application filed February 5, 1931. Serial No. 513,547.

The invention relates to an improvement in hurdles of the type used in racing or for athletic purposes by persons or horses, and in fact for any purpose for which such type of hurdle can be used.

Among the objects of the invention is to provide a hurdle having any one or all of the following capabilities: One in which the hurdle, will automatically and quickly return to its normal or regulation position when turned from such position; one in which the hurdle bar when hit by a hurdler will be deflected and will not rise above its normal or regulation position during the period of the deflection; one in which the hurdle bar will be easily deflected from its normal or regulation position, the bar being so supported as to possess relatively little inertia, so avoiding tripping when the bar is hit by the foot of a hurdler; one in which a foul will be indicated following such deflections of the hurdle as requires the registration of a foul; one easily convertible into a high or low hurdle; and one in which the hurdle bar may become released from the standard under certain circumstances when struck by a hurdler.

The invention can best be seen and understood by reference to the drawings in which—

Figure 1 is a front elevation of the hurdle according to one embodiment of the invention.

Fig. 2 is a cross section on the line 2—2 of Fig. 1.

Fig. 3 is a side elevation of the hurdle showing especially one of its standards and associated foul-indicating device, these parts being shown in full and dotted lines to indicate different relative positions occupied by them, the full lines indicating the parts when the hurdle is in a normal or regulation position, and the dotted lines indicating the parts when the hurdle is in a deflected position.

Fig. 4 is a side elevation of the hurdle like Fig. 3 excepting that the relative positions of the standard and foul-indicating device are shown after return of the hurdle to a normal position following such deflection of

the hurdle as has required the registration of a foul.

Fig. 5 is a vertical cross section of a detail of construction.

Fig. 6 is a front elevation of the hurdle according to another embodiment of the invention, one of the standards being shown partly in vertical cross section.

Fig. 7 is a cross section on the line 7—7 of Fig. 6.

Fig. 8 is a side elevation of the hurdle shown in Fig. 6 when occupying a normal or regulation position.

Fig. 9 is a side elevation like Fig. 8 excepting that the hollow base portion of the standard is cut away in part for showing the general structure thereof and the contained mechanism for indicating a foul.

Fig. 10 is a side elevation like Figures 8 and 9 excepting that the standard is shown retained in a deflected position by the foul indicating device following such deflection of the hurdle as has required the registration of a foul.

Fig. 11 is a section in enlarged detail of a portion of the structure shown in Fig. 10.

Figs. 12, 13 and 14 show in side elevation a modified structure in which the base portion of the hurdle is fitted with jointed or articulated members assisting in the support of the standard as occasion requires, Fig. 12 showing these members closed, Fig. 13 showing the members open, and Fig. 14 showing the members open and the standard occupying a tipped or rocked position.

Fig. 15 and 16 are front elevations showing the hurdle fitted with a reversible frame carrying the hurdle bar and by which the hurdle may be converted into either a low or high hurdle, Fig. 15 showing the conversion into a low hurdle and Fig. 16 the conversion into a high hurdle, these figures show also a modified form or type of hurdle bar.

Fig. 17 shows in enlarged detail a portion of the structure shown in Figs. 15 and 16.

Fig. 18 is a section on the line 18—18 of Fig. 17, and

Fig. 19 shows in perspective a detail of a modified form of the hurdle bar as shown in Figures 15, 16 and 17.

Referring to the drawings:

1 represents the respective standards and 2 the hurdle bar borne by the standards. Each of the standards comprises a base portion 3 and upright 4. Each of the standards is so made that it will rest upon the ground or base of support in a proper normal or regulation position but with the capability of being rocked or deflected from such position, and with the further capability of stable equilibrium by which it will return to its original position after such deflection or displacement. To this end the base of the standard is preferably a somewhat heavy or weighty body presenting on its under side a rounding or cylindrical surface 5, while the centre of gravity of the standard, located in the base and lying as it does within a vertical line passed through the point or axis of support when the standard is in its normal or regulation position, will be raised on deflection of the standard whereupon gravity will tend to return the standard to its normal or regulation position after such deflection. When the standards are in their normal or regulation positions, they, and the crossbar carried by them, will be easily deflected inasmuch as the centres of gravity of the standards occupy positions relatively near their points of support as compared with the heights of the standards. This capability practically eliminates the danger of a hurdler tripping in case his foot fails to clear the top of the hurdle bar for little percussion results from engagement with the hurdle bar since the inertia of the hurdle bar and combined standards is much less than that of the ordinary form of hurdle. Moreover when the standards are deflected as by the action just mentioned the hurdle bar will not rise above its normal or regulation position during the period of deflection, thereby possessing advantage over the ordinary hurdle in which the crossbar is raised when the hurdle is deflected often causing the hurdler to fall.

The standards may be of any suitable material or materials and may have any suitable form of structure provided the capabilities just referred to are retained.

50 The hurdle bar 2, extending crosswise the two standards, rests to fit at its opposite ends within slots 6 cut in the tops of the standards. That portion of the hurdle bar lying between the standards bears a strip 7 on its under side. This strip is wider than the thickness of the main bar and by the bearing of its ends against the uprights of the standards determines the spaced positioning of the standards. That portion of the hurdle bar lying 60 above the strip 7 is preferably covered with a blanket of thick felt or other soft substance 8 which reduces to a minimum shock by contact with the bar.

For the purpose of indicating and registering a foul provision is made as follows:

Each standard, and especially the upright portion of the standard, is provided with a relatively long cut-out portion 10 forming a housing within which is contained a pendulum comprising a rod 12 with flat sides and a bob 13 on the lower end of the rod. The pendulum is hung suspended from a pin 14 passed laterally through the upright and through the upper end of the rod 12 at the top end of the housing, and this pin forms the axis on which the pendulum swings.

When the standard is in its normal or regulation position the pendulum lies contained within the housing. Bearing against the flat side of the bar 12 of the pendulum thus contained at a point just below the pin 14 is a spring-pressed bolt 16. This bolt is arranged within a bent strap forming a casing 17 on the side of the upright portion of the standard. The bolt passes from outside the casing through an opening 18 in it, thence through an opening 19 in the side of the upright and extends to engage the pendulum bar as aforesaid. Fixed to the bolt within the chamber of the casing is a collar 20, and arranged upon the bolt between this collar and the casing is a spring 21 tensioned to effect a normal projection of the bolt. That portion of the bolt extending outside the casing is provided on its end with a thumbpiece 22 by which the bolt may be retracted. In the normal setting of the parts when the standard is in its normal or regulation position and the pendulum is contained within the standard as aforesaid, the spring-pressed bolt will simply bear against the flat side of the bar 12 of the pendulum. When the upright is deflected from its normal or regulation position, as for example when the hurdle bar is struck by a hurdler, the pendulum continuing to maintain its gravitated position will move out of its housing. If the deflection of the standard is sufficient, the pendulum will move so far relatively to the standard that the spring-pressed bolt bearing against the side of the pendulum bar will be released to slip by the side of the bar substantially as shown in the dotted lines of Fig. 3 and while thus projecting it will operate to prevent the return of the pendulum into its housing when the standard automatically returns to its normal or regulation position. Thus the pendulum will be left for indicating a foul substantially as shown in Fig. 4.

Afterward the pendulum can be returned into its housing in the upright simply by withdrawing the bolt after which the bolt may be released to bear against the side of the pendulum bar.

In Fig. 6 there is shown a modification of the invention in that the hurdle is shown equipped with a foul-indicating device especially adapted for a construction in which the upright portions 25 of the standards rising from bases 26, are equipped with adjustable

extensions 27 by which the hurdle bar mounted on the extensions may be raised to a determinate elevation. The extensions 27 are arranged to slide in ways 28 formed in the uprights and are secured in adjusted position by means of clamps 29. The base portion 26 of each of the standards is made hollow, access being had to the interior thereof through a lid 30 located on the upper side of the base and secured to the base by a hinged connection 31. Located in the chambered interior of the base is a weight 33 made preferably cylindrical in form. When the standard is in its normal or regulation position the weight rests upon a block 34 and exerts no displacing or deflecting influence upon the standard. The block 34 is contained within a housing 35 formed within the bottom wall of the base, and is hinged to the wall by a connection 36 by which the block may be turned into an angular position with relation to the base and socket. (See Fig. 11.) Interposed between the forward free end of the block and the base wall at the bottom of the housing 35 is a spring 38 seated within an opening 39 formed in the block. When the weight 33 is resting upon the block it will hold the block 34 in a downturned position within its housing, the spring 38 being then compressed. When the hurdle is deflected, however, or deflected in a sufficient amount to require the registration of a foul, then (as the hurdle is deflected) the weight 33 will roll forward off the block 34 into that portion of the chamber lying forward of the block. This permits the forward end of the block to be raised by the spring, whereupon the block will function as a stop preventing the return of the ball as the hurdle tends to right itself. The displaced position of the weight having changed the position of the centre of gravity of the entire hurdle, the weight will operate to hold the hurdle in its deflected position substantially as shown in Fig. 10 thereby indicating a foul.

In Figs. 12 to 14 the base of the standard is provided with wings 40, 41 adapted and arranged to either occupy a folded out-of-the-way position when the standard will function substantially like the standard previously described or, when arranged to occupy an extended operative position, will assist in the stable support of the standard and while permitting of its rocking or deflection, will curb such action, and after deflection will assist in quickly restoring the standard to its normal upright and regulation position. To this end the base is provided with a flat top surface 42 and the wings 40 are hinged respectively by connections 43 to the front and rear of the base along the meeting lines between the flat top surface of the base and its rounding bottom surface. When the wings are in their out-of-the-way inoperative position they fold inwardly as shown in

Fig. 12 to rest upon the base and the base becomes to all intents and purposes substantially like the base of the standards previously described. When open the wings turn outward and rest upon the ground or surface on which the base proper is resting with extension forward and rear of the base. When thus open and extending the wings will give support to the base and standard for maintaining the standard in a normal upright position, but will at the same time permit of the rocking or deflection of the standard. Upon deflection of the standard it will rock upon its base and at the same time the forward wing 40 will be made to slide along the ground or surface on which the wing is resting, while the rear wing 41 will be lifted above this surface. (See Fig. 14.) This action will tend to curb the rocking of the standard, at the same time will permit it. Inasmuch as the rear wing 41 has been raised above the surface, on deflecting the standard, the weight of this wing on the base will cause the standard to quickly return to its normal upright position after rocking or deflection.

In Fig. 15 there is shown combined with the standards means by which the hurdle may be quickly transformed from a low hurdle to a high hurdle with hurdle bar at standard height in both instances. Two hurdle bars are provided 45 and 46, respectively. These bars are borne by a frame comprising side bars 47 connecting crossbars 48. The frame is pivoted to the two standards by pivotal connections 49 between the uprights of the standards and the side bars of the frame. The two hurdle bars 45 and 46 extended between the side bars occupy determinate positions, respectively with relation to the pivotal centre or axis on which the frame turns. Of these the hurdle bar 45 will be supported to lie such distance above the axis of the frame, when the frame is occupying an upright position, that the hurdle bar will occupy a position requisite for forming a low hurdle. On the other hand the hurdle bar 46 will be spaced such distance away from the axis of the frame that, when the frame is turned to an upright position with the hurdle bar 46 uppermost, it will occupy a position requisite for forming a high hurdle. The frame is held in either turned position for forming either a low or a high hurdle by means of bolts 50 passed through the uprights of the standards and entering sockets or openings 51 formed in the side bars of the frame. Each bolt is carried by and maintained in a normal engaging position by means of a spring 52 fastened to the side of the standard, and the bolt may be withdrawn permitting of the frame being turned by retracting the spring.

Instead of the hurdle bar being made of wood or like substance it may be made of

textile material or fabric, and preferably elastic webbing. An example of such type of hurdle bar is shown in Figs. 15 and 16 where the frame is provided with hurdle bars 5 of the textile type or webbing. Here the ends of the fabric strip or webbing are turned back upon themselves and cemented or stitched to enfold and hold small dowels or pins 53. The hurdle bars thus fitted with 10 doweled ends are retained in operative taut positions by means of clips 54 on the uprights of the standards which grip the doweled ends of the hurdle bars, thereby holding them securely in place. The bars are 15 releasable by pulling their doweled ends from the clips, and this effect will be obtained in case a hurdler does not top the bar, but strikes the same violently. In such case the hurdle bar when struck will loose itself from 20 the clips, and the detachment of the hurdle bar may register a foul.

Having thus fully described my invention, I claim and desire to secure by Letters Patent of the United States:—

25 1. A hurdle of the character specified comprising a set of standards, a hurdle bar borne by the standards, each of said standards including a base portion and an upright upstanding therefrom, said base portion of 30 the standard having a curved under surface whereby the standard may be rocked and its upright deflected, and the centre of gravity of each of said standards being so arranged that the standard will possess stable equilibrium when occupying an upright position 35 and will automatically return to such position after rocking and deflection of its upright.

40 2. A hurdle of the character specified comprising a set of standards, a hurdle bar borne by the standards, each of said standards including a base portion and an upright upstanding therefrom, said base portion of the standard having a curved under surface 45 whereby the standard may be rocked and its upright deflected, and the centre of gravity of each of said standards being so arranged that the standard will possess stable equilibrium when occupying an upright position 50 and will automatically return to such position after rocking and deflection of its upright, and means for indicating a foul when said standards are rocked and the uprights thereof deflected in a determinate amount.

55 3. A hurdle of the character specified comprising a set of standards, a hurdle bar borne by the standards, each of said standards including a base portion and an upright upstanding therefrom, said base portion of the standard having a curved under surface 60 whereby the standard may be rocked and its upright deflected, and the centre of gravity of each of said standards being so arranged that the standard will possess stable 65 equilibrium when occupying an upright po-

sition and will automatically return to such position after rocking and deflection of its upright, a weight connected with one of said standards and adapted to occupy a normal gravitated position with relation thereto when the standard is in an upright position and to occupy a changed position when the standard has been rocked and the upright thereof deflected in a determinate amount, and means for holding the weight in said changed position.

4. A hurdle of the character specified comprising a set of standards, a hurdle bar borne by the standards, each of said standards including a base portion and an upright upstanding therefrom, said base portion of the standard having a curved under surface whereby the standard may be rocked and its upright deflected, and the centre of gravity of each of said standards being so arranged that the standard will possess stable equilibrium when occupying an upright position and will automatically return to such position after rocking and deflection of its upright, a pendulum hung on one of said standards and occupying a normal gravitated position with relation thereto when the standard is in an upright position, and means whereby the pendulum will be maintained to occupy a changed gravitated position with relation to the upright of the standard when the standard has been rocked and the upright deflected in a determinate amount.

5. A hurdle of the character specified comprising a set of standards, a hurdle bar borne by the standards, each of said standards including a base portion and an upright upstanding therefrom, said base portion of the standard having a curved under surface whereby the standard may be rocked and its upright deflected, and the centre of gravity of each of said standards being so arranged that the standard will possess stable equilibrium when occupying an upright position and will automatically return to such position after rocking and deflection of its upright, a pendulum hung on one of said standards and occupying a normal gravitated position within the upright of the standard when the standard is occupying a normal upright position, and means whereby the pendulum will be maintained to occupy a gravitated position outside the upright of the standard within which it is normally contained when the standard has been rocked and the upright thereof deflected in a determinate amount.

6. A hurdle of the character specified comprising a set of standards, a hurdle bar borne by the standards, each of said standards including a base portion and an upright upstanding therefrom, said base portion of the standard having a curved under surface whereby the standard may be rocked and its upright deflected, and the centre of gravity 125 130

- of each of said standards being so arranged that the standard will possess stable equilibrium when occupying an upright position and will automatically return to such position after rocking and deflection of its upright, a pendulum hung on one of said standards and occupying a normal gravitated position within the upright of the standard when the standard is occupying a normal upright position, and a spring-pressed pin arranged to bear against the side of the pendulum bar when the pendulum is occupying its normal gravitated position as aforesaid and will slip by said bar for locking the pendulum outside the upright in which it is normally contained when the standard has been rocked and the upright deflected in a determinate amount.
7. A hurdle of the character specified comprising a set of standards, a hurdle bar borne by the standards, each of said standards including a base portion and an upright upstanding therefrom, said base portion of the standard having a curved under surface whereby the standard may be rocked and its upright deflected, and the centre of gravity of each of said standards being so arranged that the standard will possess stable equilibrium when occupying an upright position and will automatically return to such position after rocking and deflection of its upright, a weight contained within the base portion of one of said standards and adapted to occupy a changed position when said standard has been rocked and the upright thereof deflected in a determinate amount, and means for holding the weight in said changed position.
8. A hurdle of the character specified comprising a set of standards, a hurdle bar borne by the standards, each of said standards including a base portion and an upright upstanding therefrom, said base portion of the standard having a curved under surface whereby the standard may be rocked and its upright deflected, and the centre of gravity of each of said standards being so arranged that the standard will possess stable equilibrium when occupying an upright position and will automatically return to such position after rocking and deflection of its upright, a weight contained within the base portion of one of said standards, a pivoted block on which said weight is adapted to rest when the standard is in a normal upright position and to occupy a changed position in relation to said block when the standard has been rocked and the upright thereof deflected in a determinate amount, and means whereby the block will function as a stop to hold said weight in its changed position.
9. A hurdle of the character specified comprising a set of standards, a hurdle bar borne by the standards, each of said standards including a base portion and an upright upstanding therefrom, said base portion of the

standard having a curved under surface whereby the standard may be rocked and its upright deflected, and the centre of gravity of each of said standards being so arranged that the standard will possess stable equilibrium when occupying an upright position and will automatically return to such position after rocking and deflection of its upright, and a wing hinged to the base portion of each of said standards and adapted and arranged to occupy a folded position on said base portion or an unfolded position in extension of said base portion.

10. A hurdle of the character specified comprising a set of standards, a hurdle bar borne by the standards, each of said standards including a base portion and an upright upstanding therefrom, said base portion of the standard having a curved under surface whereby the standard may be rocked and its upright deflected, and the centre of gravity of each of said standards being so arranged that the standard will possess stable equilibrium when occupying an upright position and will automatically return to such position after rocking and deflection of its upright, wings hinged to the opposite fore and aft ends of the base portion of each of said standards and adapted and arranged to occupy folded positions resting upon said base portion or unfolded positions in extension thereof.
